UNITED STATES PATENT OFFICE.

VAUGHN M. ELLIS, OF SEATTLE, WASHINGTON.

DESIGN FOR A BADGE-BUTTON.

No. 37,887.

Specification for Design.

Patented March 13, 1906.

Application filed February 10, 1906. Serial No. 300,543. Term of patent 3½ years.

To all whom it may concern:

Be it known that I, VAUGHN M. ELLIS, a citizen of the United States, residing at Seattle, in the county of King and State of Washington, have invented a new, original, and ornamental Design for Badge-Buttons, of which the following is a specification, reference being had to the accompanying drawing, showing a face view of a button embodying my design.

I claim—

The ornamental design for a badge-button, as shown.

VAUGHN M. ELLIS.
